UNITED STATES PATENT OFFICE

CARL W. SWAN, OF CHICAGO, ILLINOIS, ASSIGNOR TO TELETYPE CORPORATION, OF CHICAGO, ILLINOIS, A CORPORATION OF DELAWARE

SELECTING APPARATUS

Application filed January 12, 1929. Serial No. 332,136.

The present invention relates to selecting apparatus and more particularly the invention relates to apparatus selectively responsive to code combinations of selecting conditions especially adapted for the operation of printing telegraph mechanisms.

In printing telegraph apparatus of the permutation code type, selecting mechanisms are employed that are operated in accordance with received code combinations of impulses to select characters to be printed on a tape or page. The energy received over the line available for the control of the selecting mechanism is usually comparatively small, and it is therefore desirable to provide selecting mechanisms readily responsive to comparatively small currents. Also because of the high speed of operation demanded in modern printing telegraph operation it is desirable to reduce to a minimum the operations of the selector and printing mechanisms to increase the durability and life of and to reduce the wear and tear on the mechanisms as much as possible.

Accordingly one of the objects of my invention is to provide selecting apparatus in which a minimum amount of energy is required to control the selective operation thereof.

Another object of my invention is to provide selective mechanisms and printing mechanisms in which the necessary movements of parts are minimized.

Still another object of my invention is to provide a selecting mechanism in which the selector members are moved from position to position in accordance with received code combinations of impulses by a local and continuous operating source of power released to operate the selectors under control of electromagnetic means responsive to received signalling conditions.

A further object of the invention is to provide novel selecting mechanisms embodying a plurality of permutation elements moved only in a single direction to different settings for succeeding selecting combinations.

Still further objects of my invention are such as may be obtained by utilization of

the various combinations and subcombinations hereinafter more fully set forth and as defined by the scope of the appended claims.

Referring to the drawings:—

Figure 1 is a plan view of a preferred embodiment of my invention as applied to a type wheel tape printer.

Figure 2 is an end view with parts broken away, looking in the direction of the arrows A—A in Figure 1.

Figure 3 is a vertical sectional view taken along line B—B of Figure 1.

Figure 4 is a sectional view with parts broken away taken along line C—C of Figure 1.

Figure 5 is a view similar to Figure 2 showing the parts in a different position.

Figure 6 is a sectional view taken along line D—D of Figure 5 with parts broken away.

Figures 7 to 13 are fragmental views showing the selecting or permutation disks used in my invention.

Figure 14 shows a modified form of selecting or permutation disc for use in the invention.

Figures 15 to 17 are more or less diagrammatic views showing modifications of my invention.

As shown in the drawings energy is supplied to the mechanism by a motor (not shown) which drives shaft 1. Mounted on and rotatable with shaft 1 is gear 2 which meshes with and drives gear 3. Gear 3 is supported on and drives main selector printing and drive shaft 4. Secured to gear 3 by suitable screws 5 is a typewheel 6 on the circumference of which are mounted the letters of the alphabet, numerals, and characters to be printed as indicated at 7.

Shaft 4 is journaled in anti-friction bearings 8 supported in printer side frame members 9 and journaled on central section 10 thereof between side frames 9 are six selector disks 11 and a selector operating disk 11'. Slidably keyed on section 10 of shaft 4 and interposed between adjacent ones of disks 11 and the disk 11' are friction drive clutch disks 12 a coil spring 13 (Figure 3) interposed between discs 14 and 15 reacts

against the left side frame 9 and discs 11 and 12 forcing the discs into frictional driving contact with each other, the right end disc 12 being forced against an end plate 16 secured to shaft section 10 and abutting against a shouldered section 18 thereof. As the shaft 4 rotates, the friction disks 12 are driven and tend to rotate selector disks 11.

As shown in Figures 4 and 7 to 13, each selector disk has one or more stop notches 19 cut in its circumferential edge, adapted to be engaged by noses 20 of the selector controlling pawls 21. Two pawls 21 positioned diametrically opposite each other are provided for each of the disks 11, while one pawl is provided for the disk 11'. As shown by the arrows (Figures 7 to 13) the disks tend to rotate counter clockwise in operation but are normally held from rotation by noses 20 of the pair individual to each disk 11 being normally engaged with one of the notches 19 as shown. Each of the pawls 21 is mounted on and rotatable with a shaft 22 individual thereto by means of set screw 23.

As will be clear from the description thus far given the disks 11 are normally held from rotation by the noses 20 of pawls 21 which engage notches 19 in these disks. As will be described hereinafter, pawls 21 are selectively rocked in a clockwise direction in accordance with received code combinations releasing selected ones of the disks for rotation until the next notch in the released disk is engaged by the opposite pawl individual thereto.

Shafts 22 are rotatably journaled in suitable bearings formed in side frames 9 and secured to the right ends thereof as viewed in Figure 3 are the marking control levers 25 and spacing control levers 26 controlling the positions for discs 11, and the selector operating control lever 26' controlling the operating disk 11'.

Pawls 21 and arms 25, 26 and 26' individual thereto are so arranged that the noses 20 thereof ride on the periphery of disks 11 and 11' and drop into notches 19 by the action of gravity in operation of the mechanism.

An operating lever 27 is provided to selectively actuate levers 25, 26 and 26' in accordance with received combinations of signalling conditions as will more fully hereinafter appear. Lever 27 is slidably supported on dowels 28 and 29 carried by plate 30 rotatably mounted on the end of main drive shaft 4. Plate 30 is frictionally driven by main shaft 4 through friction disk 31 and clutch plate 32, splined for longitudinal movement on the main drive shaft 4. Friction disc 31 is forced into frictional engagement with the plate 30 by means of a spiral spring 33 interposed between bearing 8 and clutch plate 32. As shown in Figure 4, in

unactuated position of the mechanism lever 27 engages stop member 35 and is held against rotation. In response to a start impulse, arm 27 is shifted endwise out of engagement with stop member 35 and is released for rotation. As will be clear from the above, the main shaft 4 then rotates arm 27 through the action of friction disc 31 and plate 30.

Rotatably connected to the central portion of arm 27 is one end of a lever arm 36, the opposite end of which is pivotally connected by means of a pin 37 to the armature 38 of the line electro-magnet 39. Magnet 39 may be of any well known construction but is preferably a sensitive polarized magnet provided with a magnetized core 41 and divided windings 42. As shown, armature 38 extends through windings 42 and is pivotally supported at 43 between the sections of winding 42 and is limited in its movement by the poles 44 of core 41. As the armature 38 oscillates on pivot 43 in response to energizations of windings 42 it in turn oscillates the lever arm 36 in a longitudinal direction and lever 27 is in turn moved axially with respect to the main shaft 4. At the extreme left position of the armature 38 the path of the arm 27 as it rotates does not include control arms 25, but does include the control arms 26 and 26', and when armature 38 is moved by the electromagnet to its opposite or right hand position in response to a marking impulse and the arm 36 accordingly moves lever 27 to its right hand position in Figure 3, the path of the rotating arm 27 includes control arms 25 and not the control arms 26 and 26'. Accordingly as lever 27 is rotated by shaft 4 it will engage and rock the control arms 25, 26, and 26' in a manner depending upon the energization of magnet 39.

The electromagnet 39 is operated in response to received code combinations of impulses, the magnet being as is well known in the art, responsive to impulses transmitted over a signalling line extending from a remote transmitting station. The shaft 4 is driven at such a speed that the arm 27 is rotated in synchronism with the signalling impulse so that it is successively in operative position with a pair of arms 25 and 26 associated with a disk simultaneously with the receipt of a selecting condition allotted to the particular disk controlled thereby. As the lever 27 comes into operative relation with a pair of arms 25 and 26, the character of the received impulse at that instant will determine whether the lever 27 will be moved into engagement and rock the corresponding marking or spacing control arm 25 or 26. As lever 27 rotates past each pair of control arms 25 and 26 individual to the selector disks either an arm 25 or an arm 26 is moved a distance sufficient

to release the tooth 20 of the pawl 21 from notch 19 depending upon whether the lever 27 is in marking or spacing position. If the pawl individual to the actuated arm is 5 in engagement with a notch 19, the selected disk 11 will be released and will rotate until it engages the nose 20 of the opposite pawl 21. If the selected disk is held against rotation by the opposite pawl 21 individual 10 thereto, then the disk is in proper position for the selection and no rotation thereof will occur. It will accordingly be seen that rotation of selector disks occurs only when necessary to shift the position thereof for 15 the succeeding selection, thereby reducing the disk movements to a minimum. It will therefore be clear that the selector disks have no normal position to which they are restored, but are latched in their marking 20 or spacing positions until a change is required in a succeeding selection, and that received selecting impulses merely function to operate the latches to release the disks when necessary to permit movement to the 25 position in accordance with the character of the received impulse or condition. In this manner all of the selector disks are operated in accordance with the received code combinations of impulses and assume 30 a predetermined relative position with respect to each other at the end of the code combination of impulses.

The nature of these disks and the manner in which they cause the printing of a pre- 35 determined character after they are set up in a predetermined alignment will now be described. Referring to Figures 7 to 13 it will be noted that the disks 11 each of which, as will be clear from the above, hav- 40 ing a marking and spacing position, is pro- 45 vided with a series of small holes 51 ar- ranged differently in each disk so that for each different combination of the disks a different set of holes 51 will be aligned. 50 Loosely carried in each of these holes 51 is a ball 52 (Figures 3 and 6) of a diameter sufficiently large to prevent the ball from falling out of the opening but sufficiently small to permit freedom of movement of the 55 ball in its hole 51.

Accordingly, when the disks 11 are selectively positioned with respect to each other in marking and spacing position, there will be one set of holes and balls therein in alignment. As will be understood by those skilled in the art, each code combination of 55 selecting conditions is preceded by a start condition which frees lever 27 from engagement with stop 35 for a complete revolution, 60 and is followed by a stop condition which causes lever 27 to engage stop 35 and come to rest at the end of each revolution. For any one combination of positions of the disks determined by code combinations of 65 selecting conditions there is only one align-

ment of the balls possible and this alignment will invariably occur for the same relative positions of the disks. Similarly at other relative positions other openings and other balls will be aligned at other positions about the circumference. For each setting of the first five disks 11 there can be 70 32 such alignments by permutation.

In order to eliminate the need of the shift mechanism controlled by a code combination of signals I provide a sixth disk 11 which is operated in response to a shift impulse. So long as characters in the same case position are to be printed this disk is not operated. When however, a character in a different case position is to be printed, the shift control disk 11 is released for rotation causing printing in the opposite case from the preceding character as will be described more fully hereinafter.

The receipt of each code combination of signalling conditions and the corresponding alignment of the disks 11 selects the character and the selection is then transferred by the operation of disk 11' which is invariably released by actuation of control arm 26' by engagement with lever 27 near the end of its revolution. Disk 11' has a hole 51 and ball 52 for each possible alignment of the disks 11 so that when it is released one of the balls 52 thereby will be moved into alignment with the aligned balls in disks 11 thereby forcing the aligned balls to the left in Figure 3.

Opposite each position of alignment of balls 52 there is provided a setting pin 53 slidably mounted for longitudinal movement in suitable holes formed in the left side frame 9. Each pin 53 is provided with two grooves 54 and 55. A coil spring 56 nesting in an annular groove 56' of side frame 9 snaps into grooves 54 or 55 and holds pins 53 in the positions where set. After each printing operation as will more fully hereinafter appear pins 53 are restored to their right hand position in which the spring 56 lies in the left hand groove of each of these pins. As illustrated when the balls opposite one of these pins are in alignment and disk 11' is operated, the aligned balls push 100 toward the left (Figure 3) and move a selected pin 53 opposite which they are in alignment in a longitudinal direction toward the left against the action of the locking spring 56. The selected pin 53 is then in 105 operated position to the left with its end protruding beyond the other pins and spring 56 maintains the selected pin in operative position. From the above it will now be clear that one of the setting pins 53 is selected in accordance with the setting of the disks 11 and shifted to operative position. As will now be described the setting pin 53 selected and operated in turn determines 110 which of a pair of characters on the type 115 120 125

wheel contains the character to be printed, while the sixth disk 11 determines which of the selected pair of characters is to be printed.

Referring to Figures 5 and 6 it will be seen that carried on the shaft 4 is an arm 61 secured to and rotatable with the shaft 4. Pivotally mounted on the end of the arm 61 by means of pin 62 is a seeker member 63 provided with an extension 64 and a tooth 65. The seeker member 63 is normally urged in a clockwise direction about its pivot 62 by a spring 66 secured to the end thereof and to the arm 61 in any suitable manner.

Journalled on drive shaft 4 is a hub 67 of ratchet 68 provided with teeth 69 (Figs. 3, 5 and 6). Also secured to hub 67 is printing cam disk 71 having cam surface 72. The printing cam disk 71 and ratchet 68 are normally held from turning by jockey lever 73. Jockey lever 73 is secured to one end of shaft 74 which is suitably journalled in the frame work. A printing arm 75 is secured to and actuated by the opposite end 25 of shaft 74 and carries at its free end the printing roller 76 around which tape 77 passes. Feed roller 79 in frictional engagement with the tape 77 forces the tape against roller 76 and is actuated by a ratchet feed 30 mechanism of any well known construction (not shown) to feed the tape a letter space following each printing operation. Secured at one end to the base of the frame is a spring 81, the other end of which is secured 35 to the extension 82 of the crank 73 and holds the end of jockey lever 73 resiliently in engagement with cam surface 72.

The operation of the above described apparatus will now be given. As has already 40 been explained, shaft 4 is continuously driven in operation by the power supplied from the motor through motor shaft 1, and gears 2 and 3. Continuously rotating with the shaft 4 is the typewheel 6 carrying the 45 type characters to be printed. In frictional driving engagement with shaft 4 is also the normally latched member 27 which after being released by a start impulse is successively brought in operative relation with 50 either arm of the set of control arms 25 and 26 individual to each of the selector disks 11. Lever 27 is brought into operative relation with each pair of arms 25 and 26 simultaneously with the receipt of a selecting 55 condition by electromagnet 39 and depending on the character of selecting condition received at the instant when the arm 27 comes into operative relation with each pair 60 of arms the associated selector disk is released for rotation if it is not properly positioned for the selection. In this manner each of the disks 11 is successively operated in accordance with the code combination selecting conditions received and will be posi-

tioned accordingly to align a corresponding set of balls 52.

As has been explained, the first five disks 11 assume a position permitting either a "figures" or a "letters" case character to be 70 printed, and the position of the sixth disk 11 determines the character of the pair to be printed. In the mechanism disclosed, while the letters and figures characters are in separate rows as is usual in stock tickers, 75 it will be noted that the type wheel is provided with the characters and letters angularly spaced from each other so that for each angular position of the type wheel only one character may be printed. It is however to 80 be understood that my improved selector may be utilized with the letters and characters arranged in aligned pairs at each angular position of the wheel and a shift mechanism controlled by the sixth disk 11 85 may be utilized to determine the printing of the selected character of a selected pair.

Following the setting of the selector disks 11 in accordance with the code combination of impulses received, the member 27 is rotated into operative relation with a control arm 26' associated with the operating disk 11' freeing it for rotation. Disk 11' moves one of its balls into alignment with the 90 balls already aligned pushing the aligned balls and the selected setting pin 53 adjacent the aligned balls to its operative position in the path of the extension 64 of the seeker 63 as shown in Figures 5 and 6. The selected pin 53 is held in set position by spring 95 56, and the disks 11 and 11' may now be immediately reset by the succeeding code combination while the printing of the selected character proceeds thus providing an 100 overlap of selecting and printing operations. Thereafter and during the succeeding revolution of lever 27, while the printing operations now to be described take place, the selector disks 11 are set in accordance with 105 a new code.

The arm 61 with seeker 63 is continuously 110 rotating, driven by the main drive shaft 4 on which it is mounted. By means of the spring 66 the extension 64 of seeker 63 is held in a path opposite the setting pins 53. 115 When the seeker 63 reaches the selected pin 53 which has been moved to its operated position extension 64 will engage the protruding end of this pin and as the arm 61 continues to rotate the extension 64 will 120 rotate about its pivot pin 62 against the tension of spring 66 and the tooth 65 will engage one of the teeth 69 on the ratchet 68. As described above, the ratchet 68 and printing ratchet 71 are loosely mounted on the main shaft 4 but normally held from rotation by the jockey 73 which normally lies in one of the depressions of cam surface 72 such as 85. When tooth 65 engages 125 one of the teeth 69 on ratchet 68, the ratchet

is rotated a distance to move cam disk 71 a distance of one cam depression. At the end of the movement of ratchet 68 cam surface 87 (Figs. 2 and 5) on seeker extension 64 forces the selected pin inward restoring it to non-selected position, and seeker 63 is restored under the action of spring 66 and tooth 65 disengages from the tooth 69 of ratchet 68.

10 As a result however of this movement of the ratchet 68 and printing cam disk 71, the jockey 73 is rocked as shown in Fig. 5 by operation of the cam disk and shaft 74 is rotated in a clockwise direction, and printing arm 75 on shaft 74 is rotated in a clockwise direction impacting tape 77 momentarily against the character on the typewheel 6 adjacent roller 76. A character is thus printed on the tape 77. On continued 15 movement of cam disk 71 completing the distance of one tooth, jockey 73 again slides into a depressed portion of the cam and the shaft 74 is rocked in the opposite direction by tension of the spring 81 moving the printing roller 76 away from the typewheel. This movement also produces a rotation between roller 79 and printing roller 76 to move the tape a distance of one letter space for presenting a new printing surface by 20 operation of a suitable stepping mechanism of any well known construction (not shown). The cycle of operations is now completed and is repeated for each character to be printed.

35 It will be clear to those skilled in the art that the holes 51 in which the balls 52 are inserted may be arranged in any desired manner in order to provide the necessary number of selections. In the form shown 40 in Figure 14 one of the selector disks 11 is provided with one tooth and thirty two holes arranged on a semi-circle of the disk, the disk movements being a half turn. The next selector disk in this form is provided with two teeth and two groups of sixteen holes symmetrically arranged in one quarter of a turn, the disk movement being one quarter of a turn. The third selector disk is provided with four teeth and 45 four groups of 8 balls each symmetrically arranged in one eighth of a turn with a movement of one eighth of a turn. The fourth disk has eight teeth with eight groups of four ball each symmetrically arranged in one fourth of a turn with an escapement of one sixteenth of a turn. The fifth disk will have sixteen teeth with sixteen groups of two balls symmetrically arranged with an 50 escapement of 1/32 of a turn. The sixth disk is provided with 32 teeth, one ball being symmetrically arranged in 32 groups with an escapement of 1/64 of a turn. The seventh disk in this form of invention is 55 similar to the sixth disk but controlled by

only one pawl which is actuated every time the arm 27 makes a revolution.

It will also be understood by those skilled in the art that the alignment of the selector disks need not necessarily function to set 70 balls for operating a setting pin to control a typewheel. As shown in Fig 15 the disks may be provided with gear teeth 91 which mesh with teeth 92 on selector bars 93 of the notched type which are operated in various combinations in accordance with the positioning of the disks to control operation of a printer, or other selecting mechanism, or as shown in Fig. 16 each of the disks 75 may be provided with a notch 94' in which an extension lever arm 95' individual to each of five vanes 94 is operated as the disk rotates to in turn set the vanes in combinations to control operation of selective mechanisms comprising notched code bars 80 controlled by the vanes in mechanisms of a type well known to those skilled in the art.

Instead of the arrangement for rotating the selector disks shown in Figure 6, the arrangement shown in Figures 15 to 17 may 90 be employed. In these modifications, a setting marking pawl 95 individual to each selector disk is adapted to be actuated by lever 27 and through lever 96 pivoted at 97 actuates link 98 secured to the selector disk 95 11 at 99 to set the disk to marking position. A resiliently supported jockey roller 101 in slot 102 of each disk 11 and 11' holds the disk in position where set. In response to a spacing impulse arm 103 individual to each disk and suitably pivotally supported on the frame work is engaged by lever 27, and rocks arm 104 through a suitable shaft 104'. Each arm 104 is forked at its end and engages a pin 105 on the disk individual thereto. As the pawl 103 is rocked, arm 104 through pin 105 rotates the disk to its spacing position. In this manner each disk is operated to either position and remains set until its position is to be changed in a succeeding selection without the use of springs. These arrangements will be well understood by those skilled in the art as obvious applications of the selector disks, it being understood that the invention resides not in the actual type of control accomplished thereby but in the manner of setting these disks to any one of a plurality of non-normal positions and maintaining them set in that position.

Having described preferred embodiments only of my invention what I desire to secure by Letters Patent and claim as new is:—

1. In combination, a rotatable arm, a plurality of elements circumferentially arranged around the path of movement of said arm whereby said arm moves past each of said elements in succession and means responsive to received code combinations of signalling conditions for shifting said arm 125 130

in and out of alignment with said elements as said arm approaches each said element in its rotation.

2. In combination, an actuating finger, means for rotating said finger in synchronism with received code combinations of signalling conditions, a plurality of selector controlling elements circumferentially arranged in the path of said finger, and means responsive to the received code combinations of impulse conditions for moving said rotating finger in and out of alignment with said elements.

3. In combination, a plurality of selector elements arranged in a circumferential path, a rotatable finger axially movable into the circumferential path in which said elements are positioned, means for rotating said finger past each of said elements successively, and means responsive to received code combinations of signalling conditions for axially shifting said finger in and out of the path of said elements.

4. In combination, a plurality of elements arranged in a circumferential path, a finger rotatably mounted and concentric with the circumferential path in which said elements are positioned, means for rotating said finger past each of said elements successively, and means responsive to received code combinations of signalling conditions for rendering said finger operative or non-operative as it comes opposite each of said elements.

5. In combination, a rotating arm, a plurality of members arranged around the periphery of said rotating arm, means responsive to received code combinations of impulses for rocking said rotating arm in and out of the path of said members as said arm approaches each of said members, and a selector disk individual to each of said members and controlled thereby.

6. In combination, an arm, means for rotating said arm in synchronism with received code combinations of conditions, a plurality of members arranged in the circumferential path of said arm, means responsive to received code combinations of impulses for moving said rotating arm in and out of the path of each of said members, a selector disk individual to each of said members, said selector disks having no normal position, and means controlled by each of said members for operating said disks.

7. In combination, a plurality of members arranged in a circumferential path, an arm rotatably mounted and concentric with the circumferential path in which said members are positioned, means for rotating said arm past each of said members successively, means responsive to received code combinations of impulses for rocking said arm in and out of the path of said members whereby said members are operated in accordance with the code, and a selector disk individual

to each of said members and controlled by said members for selectively permitting said rotating means to operate said disks in accordance with the operation of said members.

8. In combination, a plurality of members arranged in a circumferential path, an arm rotatably mounted and concentric with the circumferential path in which said members are positioned, means for rotating said arm past each of said members successively, means responsive to received code combinations of impulses for rendering said arm operative or non-operative as it comes opposite each of said members, selector members individual to each of said first mentioned members, said rotating means tending to move said selector members to operated positions, a latching mechanism for each of said selector members for preventing the operation of said members, and means controlled by said operated members for releasing said selector members whereby said members are moved to operated position under control of said rotating means.

9. In combination, a rotating arm, a plurality of members arranged around the periphery of said rotating arm, means responsive to received code combinations of conditions for rocking said rotating arm in and out of the path of said members as said arm approaches each of said members, a selector member individual to each of said first mentioned members, each of said selector members being operable to a plurality of positions, and means controlled by said first mentioned members for operating said selector members to one of its operated positions.

10. In combination, a plurality of selector disks, said selector disks having no normal position, a source of power tending to rotate said disks, latching devices for normally preventing rotation of said disks, and means responsive to code combinations of impulses for selectively releasing said latching devices to permit rotation of said disks by said source of power.

11. In combination, a plurality of selector disks, each of said disks having a plurality of operated positions, a source of power tending to rotate each of said disks, latching means for preventing rotation of said disks, and means responsive to code combinations of impulses for releasing said latching means in accordance with the received codes for permitting predetermined rotations of said disks.

12. In combination, a plurality of selector members each having a plurality of operated positions, a source of power tending to move said selector members to their operated positions, latching mechanism for normally preventing movement of said selector members, and means responsive to code combinations

- of impulses for operating said latching mechanism to release said selector members whereby said selector members are moved to their operated positions by said source of power.
- 5 13. In combination, selector members having marking and spacing positions, a source of power tending to operate said selector members to marking and spacing positions, and means responsive to code combinations of impulses for releasing said source of power whereby said members are selectively operated to either of their operated positions.
- 10 14. In combination, a plurality of selector disks, each of said disks having a plurality of operative positions, a source of power tending to rotate each of said disks, latching devices for preventing rotation of said disks, means responsive to code combinations of impulses for releasing said latching devices in accordance with the received codes for permitting predetermined rotations of said disks, a rotating typewheel, a printing arm, and means whereby said operated selector disks control the operation of said printing arm against said typewheel at a predetermined position in the rotation of said typewheel.
- 15 15. In combination, a plurality of selector members each having a plurality of operated positions, a source of power tending to move said selector members to their operated positions, latch mechanism for normally preventing movement of said selector members, means responsive to code combinations of impulses for operating said latch mechanism to release said selector members whereby said selector members are moved to their operated positions by said source of power, a type printer having a plurality of characters, a setting arm for each character, and means whereby said setting arm individual to a predetermined character is rendered operative in response to a predetermined setting of said selector members for printing said character.
- 20 16. In combination, a plurality of selector disks, each of said disks having a plurality of operated positions, a source of power tending to rotate each of said disks, latching devices for preventing rotation of said disks, means responsive to code combinations of impulses for releasing said latching devices in accordance with the received codes for permitting predetermined rotations of said disks, a printer, and means whereby said selector disks in operated position selectively operate said printer.
- 25 17. In combination, a rotating arm, a plurality of setting members arranged in the path of said rotating arm, means responsive to code combinations of impulses for moving said arm in and out of the path of said members, whereby said members are vari-
- ably operated, a continuously rotating type-wheel rotating with said rotating arm, and means controlled by said setting members for causing the printing of one of the characters on said rotating typewheel.
- 30 18. In combination, a source of power, a rotating arm, selector mechanism, said source of power tending to rotate said arm and said selector mechanism, means for normally preventing the rotation of said selector mechanism, means controlled by said rotating arm for operating said preventing means for releasing said selector mechanism whereby it is rotated by said source of power, a continuously rotating type wheel, and means controlled by said selector mechanism for selectively operating said type-wheel.
- 35 19. In combination, a plurality of disks having holes, balls in said holes, a source of power, and means for selectively releasing said source of power to operate said disks in various combinations for aligning different combinations of said balls.
- 40 20. In combination, a plurality of selectors, each having marking and spacing positions; a source of power for moving each of said selectors from either one of its positions to the other; means individual to each of said selectors for normally preventing movement of said selectors; and means responsive to received code combinations of signalling conditions for selectively actuating said individual means to permit said source of power to operate said selectors to marking and spacing positions in accordance with received code combinations of signalling conditions.
- 45 21. In combination, a plurality of selector members each having marking and spacing positions; a source of power for operating the selector members in the same direction from marking to spacing position or from spacing to marking position; means for normally preventing said source of power from operating said selector members; and means responsive to received code combinations of marking and spacing conditions for selectively operating said last mentioned means to permit said source of power to operate said selectors to marking and spacing positions in accordance with received code combinations.
- 50 22. In combination, a plurality of rotatable disk selectors each having marking and spacing positions; a source of power for operating said selectors in the same direction from marking to spacing position or from spacing to marking position; means for normally preventing said source of power from operating said selectors; and means responsive to received code combinations of signalling conditions for selectively operating said last mentioned means to permit movement of said selectors to marking or spacing po-

sitions in accordance with received code combinations of signalling conditions.

23. In combination, a plurality of selectors, each having marking and spacing positions; a source of power for operating said selectors in the same direction from marking to spacing position or from spacing to marking position; means comprising a latching arm individual to each of said selectors and arranged in a circumferential path for normally preventing said source of power from operating said selectors; a lever finger; means for rotating said finger in timed relation with received signalling conditions; and means responsive to said received signalling conditions for operating said lever finger into or out of the path of said latching arms whereby said arms are variably operated in accordance with the impulse conditions received to release their associated selectors.

24. In combination, a plurality of rotatable disk selectors, each having alternate marking and spacing positions; a source of power for operating said selectors in the same direction from marking to spacing position or from spacing to marking position; means comprising a latching arm individual to each of said selectors arranged circumferentially with respect to each other for normally preventing said source of power from operating said selectors; a lever finger; means for rotating said finger in timed relation with received code combinations of signalling conditions; and means responsive to said received code combinations of signalling conditions for operating said lever finger into or out of the path of said latching arms whereby said arms are variably operated in accordance with the impulse conditions received to release their associated selectors.

25. In combination, a plurality of selectors, each having alternate marking and spacing positions; each of said selectors being provided with a pair of lever arms; said lever arms being arranged in a circumferential path; the lever arms of any one pair individual to a selector being arranged opposite to each other; a source of power for operating the selectors in the same direction from marking to spacing position or from spacing to marking position; a member having two extensions; means for rotating said member in timed relation with received code combinations of signalling conditions, whereby said member moves into operative relation with each of a pair of lever arms in succession; and means responsive to received code combinations of signalling conditions whereby either one or the other extension of said member is moved into the path of one of the lever arms with which it is associated at the time whereby said lever arm is operated to release its associated selector for operation from the position it is in to its alternate position.

26. In combination, a plurality of rotatable disk selectors, each having alternate marking and spacing positions; each of said selectors being provided with a pair of lever arms; said lever arms being arranged in a circumferential path; the lever arms of any one pair individual to a selector being arranged diagonally opposite from each other; a source of power for operating the rotatable disk selectors in the same direction from marking to spacing position or from spacing to marking position; a finger having two extensions longitudinally displaced from each other; means for rotating said finger in timed relation with respect to a received code combination of signalling conditions, whereby said finger moves into operative relation with each of a pair of levers in succession; means responsive to received code combinations of signalling conditions for moving said finger longitudinally whereby either one or the other end of said finger is moved into the path of one of the pair of lever arms with which it is at the time associated whereby said lever arm is operated to release its associated selector for operation to its alternate position.

27. In combination, a plurality of selectors, each having a plurality of marking and spacing positions; a pair of latches individual to each of said selectors, only one of each pair of said latches being in latching relation with its associated selector at a time; means responsive to received code combinations of signalling conditions for correspondingly operating one of each of said pairs of latches, whereby if a latching latch is operated the associated selector is moved to its alternate selecting position from that in which it previously was latched and whereby if the non-latching latch is operated said selector is not operated.

28. In combination, a plurality of selectors, each having a plurality of marking and spacing positions; marking and spacing latches individual to each of said selectors; said spacing latch being in latching relation with said selector to prevent its operation when the associated selector is in the spacing position and vice versa; means responsive to received code combinations of marking and spacing conditions for operating one of each of said marking and spacing latches individual to selectors in accordance with the code combination of conditions received whereby in response to a marking condition a marking latch is operated to release its associated selector if the selector is in its spacing position at the time for movement to its marking position and the spacing latch is not operated; and the marking latch is not operated in response to the spacing impulse while the spacing latch is operated in response to a marking impulse; the spacing latch being non-operative to effect the selec-

tor while the selector is in its spacing position.

29. In combination, a plurality of selectors, each having a plurality of marking and spacing positions; a pair of latches individual to each of said selectors, one of each pair of said latches being in latching relation with its associated selector at a time; a rotating element operating in timed relation with received signalling conditions past each successive pair of latches; and means responsive to said signalling conditions for operating said element into the path of one of said pair of fingers in accordance with the character received for operating one or the other of each pair of latches, whereby if the latching latch is operated the associated selector is moved to its alternate selecting position and whereby if the non-latching latch is operated, said selector is not operated.

30. In combination, a plurality of members arranged in pairs in a circumferential path, each member of a pair being opposite from the other member of the pair; an element; means for rotating said element in timed relation with received code combinations of signalling conditions, whereby said element is simultaneously in operative angular relation with each of a pair of members; and means for operating said element axially as it rotates whereby said element operates either one or the other of the pair of members with which it is at the time angularly associated.

31. In combination; a plurality of members arranged in pairs in a circumferential path, each member of a pair being opposite from the other member of the pair; a finger; means for rotating said finger in timed relation with received code combinations of signalling conditions, whereby said finger is simultaneously in operative angular relation with each of a pair of members; means for operating said finger axially as it rotates whereby said finger operates either one or the other of the pair of members with which it is at the time angularly associated; selector members individual to each pair of said first mentioned members, each selector member having positions individual to each of its pair of associated members; said first mentioned members normally preventing operation of said selector members; and means whereby when a predetermined one of said pairs of members is operated by said finger, its associated selector is moved to a position individual to the other of the pair of members by said first mentioned source of power.

32. In combination; a plurality of members arranged in pairs in a circumferential path, each member of a pair being diagonally opposite and longitudinally displaced from the other member of the pair; an element; means for rotating said element in

timed relation with received code combinations of signalling conditions, whereby said element is simultaneously in operative relation with each of a pair of members; means for operating said element transversely as it rotates to operate either one or the other of the pair of members with which it is at the time associated; a selector member individual to each pair of said first mentioned members each having marking and spacing positions, one of the first mentioned members controlling its associated selector member in its marking position and the other of the pair controlling its associated selector member in its spacing position whereby when the marking member is operated, the associated selector member is moved to its marking position and vice versa.

33. In combination, a plurality of selector disks, each provided with a plurality of holes; balls arranged in said holes; means responsive to receive code combinations of signalling conditions for operating said disks in various combinations, the holes in said disks being so arranged that when said disks are operated in accordance with a predetermined code combination, certain of said holes are in alignment and the balls therein are in juxtaposition with respect to each other; a member individual to each of said aligned positions and actuated when the balls individual thereto are in alignment; and means for locking said members in actuated position.

34. In combination, a plurality of selector disks each provided with a plurality of holes; balls arranged in said holes; means responsive to received code combinations of impulse conditions for operating said disks in various combinations, the holes in said disks being so arranged that when said disks are operated in accordance with a predetermined code combination, certain of said holes are in alignment and the balls therein are in juxtaposition with respect to each other; a member individual to each of said aligned positions shifted transversely when the balls individual thereto are in alignment; and means for maintaining the shifted member in shifted position independently of said balls.

35. In a printing recorder, a typewheel; a printing mechanism coacting with said typewheel; a plurality of movable members; means for setting said members in predetermined combinations; elements loosely supported by said members adapted to be brought into rigid alignment in differing combinations at the various printing positions of said typewheel; and means cooperating with said rigidly aligned elements for controlling said printing, said means thereafter being independent of said rigid alignment.

36. In a recorder a rotatable typewheel,

- printing means coacting with said typewheel; a plurality of independently movable disks, each provided with a plurality of openings; elements carried in said openings;
- 5 means controlled in accordance with received signalling conditions for selectively moving said disks to bring selected sets of said elements into rigid alignment; and means individual to said sets of rigidly aligned elements and controlled thereby for selectively controlling said printing means to cause printing of a selected character without arresting rotation of said type wheel.
- 10 37. In a recorder; a plurality of apertured selector members; means responsive to received code combinations of signalling conditions for operating said selector members; movable elements disposed in said apertures adapted for alignment in differing combinations in response to the received code combinations of signalling conditions; mechanical means operated by the alignment of said elements controlling recording operation; and means for maintaining said mechanical means in operated condition independently of said selectors.
- 15 38. In combination; a plurality of selectors; a plurality of movable elements carried by said selectors; means responsive to received code combinations of signalling conditions for operating said selectors to align predetermined ones of said movable elements, printing mechanism; means controlled by said aligned elements for selectively operating said printing mechanism; and means permitting said last mentioned means to operate in accordance with a received code combination while said selector members are reoperated in accordance with a succeeding code combination of signalling conditions.
- 20 39. In combination; a typewheel; means for rotating said typewheel; a plurality of circumferentially arranged control elements; printing mechanism controlled by said elements and coacting with said typewheel; rotatable means for operating said printing mechanism normally in non-operative position; a rotating member; means responsive to received code combinations of signalling conditions for positioning selected ones of said control elements in the path of rotation of said rotating member; and means controlled by said rotating member when it engages a control element for rotating said rotatable means causing actuation of said printing mechanism.
- 25 40. In combination, a typewheel; means for continuously rotating said typewheel; printing mechanism coacting with said type wheel; a plurality of control elements; a rotating member controlling said printing mechanism and controlled by said elements; means for selectively positioning said control elements in the path of said rotating

member; and means actuated when said rotating member engages said control elements actuating said printing mechanism.

41. In combination a typewheel; means for continuously rotating said typewheel; printing mechanism; a cam member actuating said printing mechanism; a plurality of control elements; a member rotating with said typewheel; means for selectively positioning said control elements in the path of said member; and means actuated when said member engages a control element for actuating said cam member to operate said printing mechanism.

42. In combination; a typewheel having 80 numeral and letter characters, all of said characters being angularly displaced from each other about said typewheel and said numerals being offset with respect to said letters; and means responsive to six unit 85 code combinations of selecting conditions for selectively printing said numeral and letter characters in offset relation with respect to each other; one only of said code combinations being used for each character to be recorded.

43. In combination; a typewheel having figures and letters case characters, all of said characters being angularly displaced from each other about said typewheel; and means 95 responsive to equal length received permutations of marking and spacing conditions for selectively printing said figures and letters characters in offset relation to each other, one only of said permutations being used 100 for each character to be recorded.

44. In combination, a type carrying means having figures and letters case characters; means responsive to received equal length permutations of marking and spacing conditions for selecting said characters; and means including a platen for printing the selected figures and letters characters in offset lines without causing relative shifting movement of said platen and said type carrying means.

45. In combination, type carrying means having figures and letters case characters; means responsive to received equal length 115 permutations of marking and spacing conditions for selecting said characters; and mechanism including printing means for printing the selected figures and letters characters in offset lines without causing relative shifting movement of said printing means and said type carrying means.

46. In combination, type carrying means having figures and letters case characters; means responsive to received six unit permutations of marking and spacing conditions for selecting said characters; and mechanism including impression means for printing the selected figures and letters characters in offset lines without causing relative shift- 130

ing movement of said impression means and said type carrying means.

47. In combination, a typewheel structure having figures and letters case characters; means responsive to received equal length permutations of marking and spacing conditions for selecting said characters; and mechanism including impression means for printing the selected figures and letters characters in offset lines without causing relative shifting movement of said impression means and said type carrying means.

48. In a printing telegraph receiver, a typewheel having letters and figures arranged on a surface thereof in alternate position and displaced angularly with respect to each other, means responsive to an equal length letter code for controlling the setting of said typewheel, and means controlled by one unit of the equal length letter code for determining whether letters or figures will be printed from said typewheel.

49. In a printing telegraph receiver, a typewheel having letters and figures arranged on a surface thereof in alternate position and displaced angularly with respect to each other, means responsive to an equal length letter code for controlling the setting of said typewheel, and means controlled by one unit of the equal length letter code for determining the position of said type to align either letters or figures thereon for printing as determined by the character of said unit of the letter code.

50. In a selecting device, a series of elements, means to set said elements in varying permutations, a series of members, one corresponding to each different permutation, means to operate one of said members according to one setting of said elements, and detent means to maintain said member in selected position while said elements are being set in accordance with a new permutation.

51. In a selecting device, a series of elements, means to set said elements in varying permutations, a series of pairs of members, one permutation of said elements acting to partially condition one of the pairs of members for operation, an element added to the series of elements and acting to fully condition one or the other of the partially conditioned pair of members; means to operate the fully conditioned member, and means to maintain said member in operable position while all said elements are being set in accordance with a new permutation.

52. In combination, a permutation selector including a plurality of selector discs, a plurality of elements to be selected, means responsive to received code combinations of selecting conditions for selectively operating said discs to condition one of said elements for operation, means to operate said conditioned element, and means for maintaining

said operated element in operative position while said selector discs are reoperated in accordance with a succeeding code combination of signalling conditions.

53. In combination, a permutation selector including a plurality of selector discs, a plurality of elements to be selected, means responsive to received code combinations of selecting conditions for selectively operating said discs to move one of said elements into its operative position, and means for maintaining said selected element in operated position while said selector discs are reoperated in accordance with a succeeding code combination of signalling conditions.

54. In a printing telegraph receiver, a constantly rotating typewheel, a stationary character indexing device including a plurality of elements to be selected, a character seeker rotating with said typewheel, means responsive to received code combinations of selecting conditions for selectively operating said indexing device to condition one of said elements for operation, means to operate said conditioned element, means for maintaining said operated element in co-operative relationship with said character seeker while said indexing device is reoperated in accordance with a succeeding code combination of signalling conditions.

55. In a printing telegraph, a series of characters divided into two groups, one of said groups comprising letters case characters and the other figures case characters, a selecting device comprising a series of elements operated in varying permutations, a plurality of mechanical members, one corresponding to each letter case character and one corresponding to each figure case character, one permutation of said elements acting to partially condition two of said members for operation, one of said members corresponding to a character in the letters case group and the other to a character in the figure case group, an element added to the series of permutation elements and acting to fully condition one or the other of the two partially conditioned members, means to operate the fully conditioned member, and means to record the character corresponding to the member operated.

56. In a selecting device, a plurality of permutation elements each having a marking and a spacing position, means tending to move each element, a marking latch adapted to hold a corresponding element in spacing position, a spacing latch adapted to hold a corresponding element in marking position, means to operate a marking latch to permit the corresponding element to assume its marking position, and means to operate a spacing latch to permit the corresponding element to assume its spacing position.

57. In a selecting device, a plurality of

permutation elements each having a marking and a spacing position, means tending to move each element, a marking latch adapted to hold a corresponding element in spacing position, a spacing latch adapted to hold a corresponding element in marking position, and means responsive to received code combinations signalling conditions to operate a marking or a spacing latch to permit the corresponding element to assume its marking or spacing position.

- 10 58. In a selecting device, a plurality of permutation elements each having a marking and a spacing position, means tending to move each element, a marking latch adapted to hold a corresponding element in spacing position, a spacing latch adapted to hold a corresponding element in marking position, and a single magnet adapted to operate marking or spacing latches in accordance with received code combinations of marking and spacing conditions to permit corresponding elements to assume marking or spacing positions.
- 15 59. In a printing telegraph receiver, a constantly rotating typewheel, a stationary indexing device comprising a plurality of elements, means to select one of said elements according to the character to be recorded, and means to record from said typewheel a character according to the element selected without stopping the typewheel.

- 20 60. In a printing telegraph receiver, a constantly rotating typewheel, a stationary indexing device comprising a plurality of elements to be selected, means to select one of said elements according to the character to be recorded, one only of said permutations being used for each element and one only of said characters being assigned to each element, and means to record from said typewheel a character according to the element selected without stopping the typewheel.

- 25 61. In a permutation device, a series of permutation elements movable in one direction only, each element having marking and spacing positions, and means to stop said elements in either position.

- 30 62. In a permutation device, a series of permutation elements movable in one direction only, each element having marking and spacing positions, and electromagnetic means to stop said elements in either position.

- 35 63. In a permutation device, a series of permutation elements movable in one direction only, each element having marking and spacing positions, and electromagnetic means comprising a single magnet to stop said elements in either position.

- 40 64. In a printing telegraph, a series of elements divided into two groups, all of the elements in each group having a characteristic peculiar to the group, a series of permutation members, each permutation acting to

select one of said elements, one of said permutation members acting as the sole control to select the group.

In testimony whereof I affix my signature.
C. W. SWAN.
